UNITED STATES PATENT OFFICE.

JEFFERSON BORDEN, JR., OF FALL RIVER, MASSACHUSETTS.

BREECH-LOADING FIRE-ARM.

SPECIFICATION forming part of Letters Patent No. 243,842, dated July 5, 1881.

Application filed March 14, 1881. (No model.)

To all whom it may concern:

Be it known that I, JEFFERSON BORDEN, Jr., of Fall River, in the county of Bristol and State of Massachusetts, have invented certain new and useful Improvements in Breech-Loading Fire-Arms; and I do hereby declare that the following specification, taken in connection with the drawings furnished and forming a part of the same, is a clear, true, and complete description of my invention.

My said improvements relate to that class of arms in which the barrel tilts upward at the breech, and which are automatically cocked by the tilting of the barrel.

15 The several features of my invention, after being fully described, will be specified in detail in the several claims hereunto annexed.

Referring to the drawings, Figure 1 represents, in longitudinal section, so much of a gun as is deemed necessary to illustrate my improvements as embodied therein, with the several parts in position as after firing. Fig. 2 represents the same with the barrel tilted, ready for receiving a charge, and the hammer retracted. Fig. 3 represents the same ready for firing. Fig. 4 is a plan and a side view of the locking-bar and lever for controlling it.

The barrel A (of which there may be one or two) is attached to the stock B in a manner substantially as heretofore. The hammer C slides longitudinally in a mortised guide-block, c. A mainspring, c', is fixed to said guide-block, and at its front or free end bears against a recessed abutment on the hammer. Other forms of spring may be substituted. In this instance a pin, c'', is used as the abutment. Said pin projects through the lock-casing, and is preferably serrated at its outer end to serve as a thumb-piece for letting down the hammer.

40 from full-cock, and it so projects laterally through a slot in the casing as to also serve as an indicator of the position of the hammer, and it also, with the slot, serves as a guide for the forward end of the hammer.

45 I am aware that with movable breech-blocks containing a sliding hammer a pin projecting from the hammer through the block has been heretofore employed for indicating the position of the hammer.

50 The sear c''' is pivoted to the rear end of the

hammer, and when the latter is retracted it is held in that position by the sear, its spring causing its rear end to drop and its notch to engage with the adjacent edge of the stationary guide-block.

I am aware that the sliding hammer of a needle-gun has heretofore been provided with a sear which engaged in cocking with a movable block controlled by the trigger.

55 The firing-pin c' and trigger D are substantially as heretofore. Instead of this particular type of firing mechanism, others may obviously be employed without departing from certain other features of my invention.

The safety-guard E is a rigid pendent finger projecting downward from the top casing of the breech, as shown, and is fitted, as heretofore, in a longitudinal slot therein, so as to admit of its being moved forward for preventing the lifting or firing movement of the trigger, and rearward so as not to interfere therewith.

60 The locking of the barrel in position for firing is effected by the sliding bar F, which is slotted or fitted for the reception of the lug or ear a on the under side of the barrel, near its front end. This lug, on its rear edge, is notched or recessed at a', and one end of the slot in bar F is wedge shaped, to enter the correspondingly-shaped recess a' in lug a. At the front 65 edge of lug a is a spring, a'', which, when permitted so to do, forces the locking-bar forward and causes it to engage in locking contact with the notch in the lug for locking the barrel in position. Springs have heretofore been used 70 for forcing the locking-bar forward; but I am the first to apply the spring on the lug, thus directly cushioning the stroke of the lug on the bar during the return of the barrels to their normal position. For moving the bar back- 75

ward out of engagement with said notch, thereby permitting the barrel to be tilted, I employ, as heretofore, a laterally-swinging lever, G, on the top of the breech at the handle of the gun, which is connected to a vertical rod, b, having at its lower end a cam, b', which occupies a slot, b'', in the locking-bar F. This cam in this instance engages only with the front side of said slot, this latter being long enough to permit the bar to be moved still farther rear- 80

ward after the cam and its lever have ceased to operate thereon. This bar, considered purely as a locking-bar, may be variously formed and still serve for locking and unlocking purposes; but it should have three contact-surfaces—one for being engaged by the spring a^2 on lug a for moving it forward, one for occupying the recess a' , and another with which the cam b' engages. As seen in Fig. 4 the bar is adapted for a double gun, the lever G , its pin, and cam occupying a central position on a line which separates the two barrels. The bar is shown with one slot for reception of the lugs a . If desired only for a locking-bar, it is so housed within the breech as to be capable of only such longitudinal movement as will be requisite for entering and leaving the locking-recess a' . In such case, however, the spring a^2 may be dispensed with, if not desired for its cushioning effect, and the cam b' , operated by lever G , be then wholly relied upon for causing both the locking (forward) and the unlocking (rearward) movements of the bar F , the cam-slot therein in such case being no longer than the swing of the cam, so that the latter will properly engage with both ends of said slot.

I am aware that sliding locking-bars have heretofore been so combined with tilting hammers that the latter would be cocked by the rearward movement of the bar, and that levers of various kinds have been so combined with sliding locking-bars and tilting hammers for moving said bars rearward and simultaneously cocking said tilting hammers. As employed by me, the locking-bar is also relied upon as a cocking-bar for automatically cocking or setting the sliding hammer for firing, and therefore it is made longer than would be requisite for the purpose of locking the barrel in position, and is also so mounted as to have the additional longitudinal movement requisite for its operation as a cocking-bar. It will be understood that but one sliding bar is employed, whether with one or two barrels.

The rear end of the bar F is in line with and arranged to abut, during its rearward movement, with a downwardly-projecting arm, c^5 , upon the sliding hammer (or hammers) C near the front end thereof; and the sear of the hammer being provided with the usual "half-cock" arrangement, the slight rearward movement of the bar F , operated as a locking-bar, also serves to set the hammer at half-cock. For automatically setting the hammer at full-cock I employ with the bar F a rocking cam, H , mounted in a recess in the under side of the front part of the breech upon a lateral pin, and a hinge-lug, d , projecting from the lower side of the barrel or barrels. Upon the rear edge of lug d is an inclined cam-surface, d' , near its lower end, which engages with the front arm of the rocking cam, and the rear arm of said cam engages with the front end of the locking-bar at d^2 . The contact-surfaces of lug d , cam H , and the front end of the bar at d^2 are so shaped and proportioned to each other as

to secure a smooth easy action, whereby, when the barrel is tilted, the hammer is fully cocked, and so that when the barrel is in its locked position the bar in its forward movement, actuated by the spring a^2 , may readily return the rocking cam to its normal position. The employment of the rocking cam in this combination is desirable; but the rearward movement of the bar may be attained by omitting the rocking cam as a separate element, and providing the rear edge of the lug d with an outwardly-curved cam-surface, so that it will operate as a cam for engaging directly with the front end of the bar; and therefore I do not limit certain portions of my invention to the employment of this precise rocking cam as a separate element, but claim as a feature of invention the sliding hammer and the sliding bar moved rearward for cocking the hammer by a cam actuated by the barrel in its tilting movement, whether said cam be a rocking cam, or whether it be formed upon the lug d , as indicated. Should the rocking cam be omitted, it would be desirable to provide the front end of the sliding bar with a friction-roller for smoothly engaging with the cam-surface, as heretofore with sliding bars arranged to operate with tilting hammers.

The locking of the barrel may be effected by various means heretofore known independently of the sliding bar, and the latter, with the rocking cam, relied upon solely for setting the sliding hammer at full-cock, and the lever and cam b' relied upon for setting the hammer at half-cock. The cocking of the sliding hammer may also be effected by other means well known, and the sliding bar, its cam, and lever relied upon as a half-cocking and barrel-locking device.

No devices are shown for the withdrawal of the cartridge-shells; but my improvements are such as will not preclude the employment therewith of several well-known extractors.

Having thus described my invention, I claim as new and desire to secure by Letters Patent—

1. The combination of the sliding hammer and spring, the mortised guide-block, and the sear pivoted to the rear end of the hammer and notched to engage in cocking with the adjacent surface of said guide-block, substantially as described.

2. The combination, with the sliding hammer, mounted in a stationary guide-block, of the screw or stud projecting laterally therefrom occupying a slot in the casing and serving as an external indicator of the position of the hammer, and with the slot also serving as a guide for the front end of the hammer beyond the guide-block, substantially as described.

3. The combination of the sliding bar, operating as a barrel-locking device, with the tilting barrel, its notched lug, the cam operated by the hand-lever, and the spring on the front of said lug for moving the locking-lever into and maintaining it in its locked position, and

- directly cushioning the lug with relation to the sliding bar during the movement of the barrel to its normal position, substantially as described.
- 5 4. The combination of the sliding bar, operating as a barrel-locking and half-cocking device, with the tilting barrel, its notched lug, the lever and cam, and the sliding hammer provided with the depending arm, which is 10 directly engaged by the rear end of the sliding bar, substantially as described.
- 5 5. The combination of the sliding bar, operating as a device for locking the barrel and for setting the hammer at full-cock, with the tilting barrel, having the lugs provided with the notch and cam-surface, the rocking cam, and the hammer, substantially as described.
6. The combination of the sliding bar, operating as a cocking device, with the hammer, 20 the rocking cam, and the tilting barrel provided
- with a lug having a cam-surface for engaging with the rocking cam, substantially as described.
7. The combination, with the sliding bar, operating as a device for locking the barrel and 25 cocking half and full, of the two lugs, the rocking cam, the hammer, and the cam with its lever, substantially as described.
8. The combination, with the tilting barrel, the hammer provided with a depending arm, 30 and the sliding bar engaging directly against said arm, operating with a rearward movement for cocking, of a cam which abuts against the front end of the bar and is actuated by the movement of the barrel, substantially as de- 35 scribed.
